FISHING CREEL

Gus H. Mavrakis, 135 Burlington Ave. 59102, and
Charles J. Boggio, 1214 Laurel Road, P.O. Box
1278 59101, both of Billings, Mont.

Filed May 25, 1967, Ser. No. 7,267

Term of patent 14 years

(Cl. D22—22)

FIG. 1

FIG. 2

FIG. 3

FIG. 4

FIG. 5

FIG. 6

FIGURE 1 is a top front perspective view of a fishing creel, showing our ornamental design;

FIGURE 2 is a front elevational view thereof;

FIGURE 3 is an end elevational view as viewed from the left;

FIGURE 4 is a bottom plan view;

FIGURE 5 is a rear elevational view; and

FIGURE 6 is an end elevational view as viewed from the right.

This is a continuation-in-part of design application Ser. No. D-3704, filed Sept. 2, 1966, and now abandoned.

We claim:

An ornamental design for a fishing creel, substantially as shown.
